DRY CLEANING MACHINE

Ernest Davis, Syracuse, N. Y., assignor to The Prosperity Company, Inc., Syracuse, N. Y., a corporation of New York

Application November 8, 1940, Serial No. 364,915

3 Claims. (Cl. 68—3)

This invention relates, generally, to apparatus for treating articles with a volatile fluid, and comprises a plurality of machines in which the articles are successively treated, as for instance, a dry cleaning apparatus embodying a washing machine in which the articles are washed in a liquid, as perchlorethylene, a centrifugal extractor for removing the greater portion of the liquid from the washed articles, and a drying tumbler into which air is passed through the articles 10 therein to defume or deodorize and dry the articles.

It has for its object a machine in which the articles may be transferred by the operator by hand from the washer to the extractor, from the 15 extractor to the tumbler without opening the cabinet in which the machines are enclosed, to the outlet of fumes and gases therefrom and to the inlet of outer air. More specifically, it has for its object a flexible sleeve or sleeves for receiving the operator's arm, the sleeve extending into the cabinet and being closed at its inner end and opening at its outer end through a wall of the cabinet, the sleeve being secured and sealed to said wall around the opening.

It also has for its object an arrangement of the machines in the cabinet by which such transfer is readily made.

It further has for its object a transparent window relative to the machines and the transfer means through which the operator can readily see the articles during the manipulation or transfer thereof from one machine to another.

It further has for its object a door arrangement by which the doors, when open, assume a position in which they facilitate the transferring of the articles from one machine and compartment to another, as from the washing machine to the extractor.

The invention consists in the novel features and in the combinations and constructions hereinafter set forth and claimed.

In describing this invention, reference is had to the accompanying drawings in which like characters designate corresponding parts in all the views.

Figure 1 is a front elevation of an apparatus embodying this invention.

Figure 2 is a sectional view on line 2—2, Figure 1.

Figure 3 is a vertical longitudinal sectional view on the plane of line 3—3, Figure 2.

Figure 4 is a sectional view on line 4—4, Figure 3.

Figure 5 is a fragmentary sectional detail view 55

illustrating one operation by the operator through the flexible sleeve.

The invention, as here shown, is embodied in a dry cleaning apparatus including a washing machine designated generally as 1, a centrifugal extractor 2, and a defumer and drying tumbler 3, these being enclosed in a gas-tight cabinet 4. The cabinet is preferably provided with partitions 5, 6 separating the interior thereof into a washer compartment 7, extractor compartment 8, and a drying tumbler compartment 9. The washing machine may be of any suitable construction, it being here shown as comprising a clothes container, drum or hydro-wheel 10 mounted on a shaft 11 to move about a horizontal axis, the drum having one or more loading doors 12 to be brought into alignment with a loading door 13 in the outer wall of the compartment 7 for the purpose of loading the clothes or articles in the drum 10. The shaft 11 is actuated in any suitable manner, it being shown as provided with a pulley 14 located outside the cabinet, which pulley may be connected in any suitable manner to a source of power, as an electric motor. The compartment 7 is also provided with a transverse partition 15 below the washing drum 10 from which leads a valve controlled outlet 16 to the compartment 7 above the partition being also provided with a suitable inlet at 17 for the cleaning fluid. The drum 10 is also provided with unloading door openings 18 in the end wall thereof opposed to the partition 5, these doors being here shown as hinged at 19 at their edges toward the axis of the drum and as swingable or openable through a door opening 20 in the partition 5 when aligned therewith. The door opening 20 is normally closed by a door 21 hinged at 22 to the partition and swings downwardly into the compartment 9 over the edge of the basket 23 of the extractor.

In transferring the articles from the washing drum 10 to the extractor, the drum is stopped with one of the doors 18 opposite the door opening 20. The door 21 is then opened as will be hereinafter described, until it assumes the dash line position (Figure 3) and then the door 18 opens to its dash line position (Figure 3). It laps over onto the open door 21 forming therewith a chute over which the articles being removed from the drum can be passed in their transfer to the extractor basket 23.

2 designates generally the extractor, this being located in the intermediate compartment 8. It includes the basket 23 previously referred to, and an outer casing, the basket being rotatable at a

comparatively high speed in the outer casing to perform the extracting operation. It is mounted on a spindle 25 actuated in any suitable or well known manner. The casing 24 is mounted upon a transverse partition 26 in the lower portion of the compartment, this partition inclining downwardly toward the compartment 1. The casing 24 is provided with a drain opening at 27 and a pipe 28 connects the lowermost part of the chamber 8 above the partition 26 to the drain pipe 28 into which the drum compartment drains.

29 designates the tumbler or drying drum mounted in the compartment 9 on a suitable shaft 30 which is actuated in any suitable manner, it being shown as having a pulley 31 located outside the cabinet and connectable to a source of power. The actuating mechanisms for the drums 10, 29 and the extractor basket 23 form no part of the invention.

The tumbler drum 29 is also formed with a loading door 32 in the side thereof opposed to the partition 6, this door being arranged to be brought into alignment with the door 33 in the partition 6, which door is shown as hinged at 34 at its upper edge and as openable upwardly about its hinge into the dash line position (Figure 3). The door 32 is slidably into open and closed position.

When both doors are open, the articles may be lifted from the extractor by hand into the tumbler. The tumbler is also formed with a peripheral unloading door at 35 arranged to be brought into alignment with an unloading door 36 in the front outer wall of the cabinet. The compartment 9 can be cut into communication with a source of heated air which passes into the compartment 9 through a pipe 37, passes through tumbler 29 and the articles therein, and out through outlet pipe 38. The volatile fluid absorbed by the heated air is usually condensed from the outer air and the air again heated and recirculated.

The compartment 9 is also formed with a transverse partition 39 near the bottom thereof from which leads a valve controlled drain pipe 40 connected to the outlet pipe 28 leading from the compartment 7.

The means by which the articles may be transferred from one machine to another without opening the cabinet to the outlet of volatile fumes, as here shown, comprises one or more flexible sleeves 41 extending into the compartment 8 and being closed at their outer ends and alined at their inner ends with holes 42 in the front outer wall of the cabinet of the compartment 8 and being secured thereto and also sealed thereto. The closed end 43 of the sleeve is usually in the form of a glove or mitten. In the illustrated embodiment of my invention, there are two of such sleeves 41 spaced apart and located in position to easily manipulate the doors 18, 21 and 33 and to unload the articles from the washing drum 10 into the extractor and from the extractor into the tumbler 29. Also, the cabinet is provided in the front wall thereof with a transparent panel 44 between the sleeves through which the operator can view the manipulations he is performing.

In operation, the articles are loaded into the washing drum 10 through the doors 12 and 13, when the machine is idle, and then the inlet pipe for the cleansing fluid is opened to permit the fluid to fill into the compartment 7 to a predetermined level. The washing operation is performed by the drum being rotated about its axis,

usually a given number of rotations first in one direction, and then in the other direction, this alternate rotation being continued during the washing period. Then the drum is stopped with one of the doors 18 alined with the door 21. The operator then thrusts one arm into one of the sleeves 41, as seen in Figure 5, opens the doors 21 and 18 into the broken line position (Figure 3) and then pulls the articles from the drum 10 through the open doors into the extractor, and again closes the door. The extractor basket is then started rotation and the rotation continued during extracting operation. The operator then thrusts his arm into the other sleeve 41, opens the doors 33 and 32 and transfers the articles from the extractor to the drying tumbler and again closes the doors 32 and 33 and the tumbler starts in the tumbling operation, while the heated air is circulated through the compartment 9 and the tumbler drum 29, the heated air removing practically all the fumes and gases. The drum 29 is rotated until its unloading door 35 is alined with the unloading door 36, both doors opened, and the articles unloaded, as the compartment 9 is then comparatively free of fumes and gases. While the drying operation is being performed, the articles may be transferred from the drum 10 of the extractor without the outlet of fumes, due to the fact that the doors 32 and 33 in the partition 6 are closed. During the extracting operation, the washing drum 10 in the compartment 1 from which the fluid has been drained, may be opened to the outer atmosphere to be loaded with comparatively little escape of fumes, due to the fact that the doors 18 and 21 are closed.

Owing to the means or flexible sleeve 41 by which the transfer of articles may be made from the washing machine to the extractor and from the extractor to the drying tumbler, it is not necessary to open the machine at a time when there are fumes in the compartment. Hence, the machine may be operated with no discomfort or danger to the operator or other persons because of the escape of fumes.

What I claim is:

1. In an apparatus for cleansing articles with a volatile fluid comprising machines in which the articles are subjected to different treatments, a gas tight cabinet enclosing the machines, a partition therein dividing the cabinet into compartments in which the machines are respectively located, one of such machines comprising a container movable about an axis and having a door opening, and a door therefor, on the side thereof adjacent the partition, and the partition having a door opening and a door therefor, the door of the container being openable through the door opening of the partition into a position to bridge the gap between the container and the partition and the door in the partition being openable into a position to bridge the space between the partition and the machine in the next compartment, whereby the two doors form a chute over which the articles may be passed between the machines.

2. In an apparatus for cleaning articles with a volatile fluid comprising machines in which the articles are subjected to different treatments, a gas tight cabinet enclosing the machines, partitions therein dividing the cabinet into compartments in which the machines are respectively located, one of such machines comprising a container movable about an axis and having a door opening, and a door therefor, on the side

thereof adjacent the partition, and the partition having a door opening and a door therefor, the door of the container being openable through the door opening of the partition into a position to bridge the gap between the partition and the machine in the next compartment, whereby the two doors form a chute over which the articles may be passed between the machines embodying the containers and the machine in the adjacent compartment, and means for manipulating the doors and transferring the articles from the outside of the cabinet without opening the cabinet.

3. In an apparatus for treating articles with a volatile fluid comprising a washing machine, an extractor, and a defuming and drying machine, a gas tight cabinet enclosing the machines, and means by which the articles may be transferred

by hand from one machine to another, while the cabinet is completely closed to the outlet of fumes and gases therefrom and the inlet of outer air, said means comprising a pair of flexible sleeves, 5 each for receiving the operator's arm located in the cabinet, the sleeves being spaced apart and located between the washing machine and the extractor and between the extractor and the defuming machine, each sleeve being closed at its inner end and opening at its outer end through a wall of the cabinet and being secured and sealed at its outer end to said wall around the opening, and a transparent window located between the sleeves through which the operations 10 and manipulations of the articles are visible to the operator.

ERNEST DAVIS.
